CLAIM

The ornamental design for a display screen or portion thereof having an icon, as shown and described.

DESCRIPTION

The patent or application file contains at least one drawing executed in color. Copies of this patent or patent application publication with color drawing(s) will be provided by the Office upon request and payment of the necessary fee.

This application is related to U.S. Design application Ser. No. 29/658,973 and U.S. Design application Ser. No.

29/658,972, both filed concurrently with the present application, the disclosures of which are herein incorporated by reference.

FIG. 1 is a front view of a portion of a display screen showing a first embodiment of my new design for a display screen or portion thereof having an icon;

FIG. 2 is a front view of a portion of a display screen showing a second embodiment thereof;

FIG. 3 is a front view of a portion of a display screen showing a third embodiment thereof;

FIG. 4 is a front view of a portion of a display screen showing a fourth embodiment thereof;

FIG. 5 is a front view of a portion of a display screen showing a fifth embodiment thereof;

FIG. 6 is a front view of a portion of a display screen showing a sixth embodiment thereof;

FIG. 7 is a front view of a portion of a display screen showing a seventh embodiment thereof;

FIG. 8 is a front view of a portion of a display screen showing an eighth embodiment thereof;

FIG. 9 is a front view of a portion of a display screen showing a ninth embodiment thereof; and,

FIG. 10 is a front view of a portion of a display screen showing a tenth embodiment thereof.

The wavy dot-dot-dash broken-line rectangles illustrate the perimeters of portions of a display screen and forms no part of the claimed design.

The inner dot-dot-dash broken-line rectangles illustrate features of the icons and form no part of the claimed design.

**1 Claim, 5 Drawing Sheets
(5 of 5 Drawing Sheet(s) Filed in Color)**

FIG. 4

FIG. 3

FIG. 6

FIG. 5

FIG. 8

FIG. 7
